UNITED STATES PATENT OFFICE.

CLARENCE V. DOYLE, OF NEW YORK, N.Y.

LOCK.

1,281,536.

Specification of Letters Patent.

Patented Oct. 15, 1918.

Application filed February 11, 1915, Serial No. 7,487. Renewed February 25, 1918. Serial No. 219,151.

To all whom it may concern:

Be it known that I, CLARENCE V. DOYLE, a citizen of the United States, residing at the borough of Manhattan, in the county of New York and State of New York, have invented certain new and useful Improvements in Locks, of which the following is a specification, reference being had therein to the accompanying drawing.

10 My invention relates to improvements in locks, and more particularly has reference to and is illustrated in the accompanying drawings in its application to a recording lock, that is to say, a lock which discloses when it 15 is operated. Where a lock of this character and an ordinary lock are used upon the same door both locks are opened in order to gain access. The proprietor and his employee or employees usually have the key to the regular 20 or usual form of lock and the other lock employed in such a case, but the recording lock usually can be opened by the manufacturer who supplies the same and is adapted to record the time of the day or night when 25 the same is locked or unlocked. This is accomplished by a record and clock mechanism, the coöperation of which is such that when the recording lock is turned either way a mark is made upon the record which is 30 moved by the clock mechanism so that the exact time is indicated on the record. This invention does not in any way relate to the clock or record making mechanism of the recording lock and has nothing whatsoever to 35 do with the usual form of lock which is employed therewith, but has to do with a means for preventing the time lock being operated while the usual form of lock is locked.

Referring to said drawings, Figure 1 illustrates in front elevation with parts broken away an application of my invention as applied to a door hung in a wall or partition. Fig. 2 is an enlarged view looking from left to right into the jamb socket within which 45 the bolt of the recording lock is engaged. Fig. 3 is an enlarged view, partly broken away, looking from the outside of the door at the bolt of the recording lock. Fig. 4 is a cross section on the line 4-4 of Fig. 3. Fig. 5 is an edge view of the keeper illustrating a modification; Fig. 6 is a sectional view illustrating another modification; and Fig. 7 is a sectional view illustrating the primary lock locked.

50 The bolt 5 of the recording lock 6-6' it will be observed on reference to Figs. 3 and

4 is provided with a recess, hollow, or cut away portion 7, and the keeper or jamb socket 8 shown to better advantage in Fig. 2 it will be observed is provided with pins or 50 projections 9-10. The end of the pin 9 is preferably about flush with the base of the keeper 8 indicated by the dotted line 11 but the pin 10 preferably projects about equal to the depth of the recess 7 in the bolt 5 so 55 that the thickness of the body of the bolt at the recess is about equal to the distance between the end of the pin 9 or base 11 and the end of the pin 10. In order therefore to enable the bolt 5 of the recording lock to enter 70 or leave the keeper or jamb socket 8, it is necessary that the door be open a suitable distance. In such position of the door the bolt 5 may be advanced by the key 13 or may be withdrawn. If the bolt 5 is shot within 75 the keeper or socket 8 the door may then be closed owing to the fact that the pin 9 may enter the recess 7 of the bolt. When said parts are in such position the bolt 14 of the usual form of lock 15 may be turned by the 80 key 16 into the keeper or housing 17. Of course the keeper or housing 17 for the bolt 14 must be mounted upon the jamb or partition 12 in such a manner that the bolt 14 enters the keeper only when the door is fully 85 closed. When the door is locked in this position by the usual form of lock 15 it will be readily understood that it is not possible to unlock the recording lock 6 because the pin 9 within the recess 7 of the bolt 5 prevents the 90 withdrawal of the bolt by the key 13.

It will be understood that, instead of using the pin 10, the width of the interior portion of the keeper 8 may be reduced, so that the distance between the wall 19 of the 95 same, as shown in Fig. 2, and the end of pin 9, is substantially equal to the width of the bolt 5, as illustrated in Fig. 5. In other words, the wall 19, looking at Fig. 2, if brought forward as far as the inner end of 100 the pin 10, will make it unnecessary to employ said pin. Furthermore, the recess 7 in bolt 5 may, of course, be formed upon the outside of the bolt instead of upon the inside of the bolt, as illustrated in Fig. 6. In such 105 case the pin 9 may be eliminated and the distance between the lefthand wall 20 of the interior keeper 8 and the end of pin 10 opposing it, would be equal to the thickness of bolt 5. In such case the bolt 14 of the primary lock would oppose the metal at the base 17 of keeper 17 when the door is closed. 110

to prevent operation of said bolt, and the door would have to be fully closed in order to operate the recording lock and the door must be slightly opened to permit the recess 5 in the exterior of bolt 5 to receive pin 10, as indicated in dotted lines in Fig. 6. With the door thus slightly opened bolt 14 of the primary lock may enter the keeper 17 as illustrated in Fig. 7. It is therefore necessary to 10 unlock the usual form of lock 15 first so as to allow the door 18 to be fully closed in order to permit bolt 5 to clear the pin 10. The recording lock 6 cannot be locked after the bolt 14 has been locked, as it will of course 15 be understood that the recording lock bolt 5 can not be shot while the door is open because said bolt is then opposed by pin 10.

In accordance with my invention, when the usual form of lock 15 is locked the bolt 20 5 of the recording lock can not be operated to lock it because the pin 9 or 10 opposes said bolt, nor to unlock it because such pin will then be in the recess 7 and the material of the bolt at the outer end of the recess will 25 oppose said pin.

It has been known that employees have left the keys of recording locks with irresponsible persons, with instructions to operate said locks at specified times, and such 30 persons have followed such instructions, whereby such employee has been enabled to leave the place unguarded by the recording lock for a period of time. He thereby gained the advantage of leaving before the proper 35 closing hour or of arriving later than the proper opening hour, whereas the recording lock would indicate that it had been operated by the employee, at the proper time, although, as a matter of fact, it was operated 40 by an unauthorized person. A particular advantage of my invention is to deter an employee from intrusting the key of the recording lock to an unauthorized person with instructions to operate the recording lock at 45 a specified time. Said employee would not be likely to leave both locks unlocked until said specified time, but would at least lock the door by means of the usual lock 15. When the employee has so locked the door, 50 the aforesaid unauthorized person cannot operate the bolt 5 of the recording lock, and the employee would not be likely to intrust the keys of both said locks to said unauthorized person. Hence, my invention provides 55 a safeguard against the operation of recording locks by unauthorized persons for the purpose of deceiving employers.

Various modifications may be made without departing from the spirit of the inventions as claimed.

I claim:

1. The combination with a primary lock adapted to fasten a door in its closed position, of a secondary lock for said door, the 65 secondary lock embodying means to prevent

the release of said secondary locking mechanism when said door is in its fully closed position, said means being releasable by an initial opening movement of the door.

2. The combination with a primary lock 70 adapted to fasten a door in its closed position, of a secondary lock having a bolt adapted when advanced to fasten said door in its closed position, said secondary lock including means to prevent the retraction of said 75 bolt when said door is fully closed, said means being releasable by an initial opening movement of the door.

3. The combination with a primary lock adapted to fasten a door in its closed position, of a secondary lock having a bolt adapted when advanced to fasten a door in its closed position, said secondary lock including means to dog the bolt when said door is fully 80 closed, said means being releasable by an initial opening movement of the door.

4. The combination with a primary lock adapted to fasten a door in its closed position, of a secondary lock also adapted to fasten said door in its closed position, said 90 secondary lock including means to prevent the advance or retraction of the bolt of said secondary lock when the door is fully closed, said means being engageable by final closing movement of the door and releasable by initial opening movement of the door.

5. The combination with a primary lock adapted to fasten a door in its closed position, of a secondary lock also adapted to fasten a door in its closed position, said secondary lock including means to prevent the advance of the bolt of said secondary lock when the door is held in its closed position by the primary lock, said means being disengageable by initial opening movement of the 105 door, after the primary lock is unlocked.

6. The combination with a locking bolt for a door, of a keeper adapted to receive said bolt, the bolt having a recess, and the keeper having a projection engageable in 110 said recess by final closing movement of said door, to dog the bolt, and disengageable from said recess by initial opening movement of the door, to permit the retraction of said bolt.

7. The combination with a primary lock for a door, adapted when engaged to hold said door in fully closed position, of a secondary lock for the same, the secondary lock including means to prevent its release when the door is so held by the primary lock, said means being disengageable by initial opening movement of the door, after the primary lock is unlocked.

8. The combination with a primary lock 125 for a door, adapted when engaged to hold said door in fully closed position, of a secondary lock for the same, having a bolt adapted when advanced to fasten said door, and means to prevent the retraction of said 130

- bolt when said door is held fully closed by the primary lock, said means being releasable by initial opening movement of the door after the primary lock is unlocked.
5. 9. The combination with a primary lock, adapted when engaged to fasten a door in its closed position, of a time recording lock, the locking mechanism of said time recording lock including means to prevent the advance or retraction of the bolt of said locking mechanism when the door upon which it is mounted is fully closed, said means being engageable by final closing movement of the door and releasable by initial opening movement of the door.
10. 10. The combination with a locking bolt for a door, of a keeper having a socket adapted to receive said bolt, the bolt having a recess in one side thereof, and the keeper having a pin projecting from one side thereof in the socket and engageable in said recess when the bolt is advanced into the socket and the door is fully closed, and disengageable from said recess by initial opening movement of the door.
15. 11. The combination with a primary lock adapted when operated to fasten a door in its closed position, of a recording lock also adapted to fasten the door in its closed position, said recording lock comprising means which render it inoperative when the door upon which said locks are mounted is closed, both of said locks being arranged simultaneously to retain the door locked.
20. 12. The combination with a primary lock adapted when operated to fasten a door in its closed position, of a recording lock also adapted to fasten the door in its closed position, said recording lock comprising means which render it inoperative when the door upon which said locks are mounted is closed, and the primary lock is locked, both of said locks being arranged simultaneously to retain the door locked.
25. 13. The combination with a primary lock adapted when advanced to fasten a door in its closed position, of a recording lock comprising means, which render it inoperative when the primary lock is locked, both of said locks being arranged simultaneously to retain the door locked.
30. 14. The combination with a primary lock adapted when advanced to fasten a door in its closed position, of a recording lock having a keeper, and means coactive between the bolt and keeper of said recording lock which render the mechanism thereof inoperative when the door is fully closed, both of said locks being arranged simultaneously to retain the door locked.
35. 15. The combination with a primary locking mechanism adapted when operated to fasten a door in its locked position, of a recording lock also adapted to fasten the door in its locked position, said recording lock comprising means which render it inoperative when the door is in its locked position and the primary lock is locked.
40. 16. The combination with a primary locking mechanism adapted when operated to fasten a door in its locked position, of a recording lock also adapted to fasten the door in its locked position, said recording lock comprising means which prevent the advance or retraction of the bolt of said recording lock when the door is in its locked position and the primary lock is locked, both of said locks being arranged simultaneously to retain the door locked.
45. 17. The combination with a primary locking mechanism adapted to fasten a door in its locked position, of a recording lock comprising means which render it inoperative when the door is in its locked position and the primary lock is locked, said means being engaged by a movement of the door before the primary lock is locked and disengaged by a movement of the door after the primary lock is unlocked.
50. 18. The combination with a primary locking mechanism adapted to fasten a door in its locked position, of a recording lock comprising means to prevent the advance or retraction of the bolt of said recording lock when the door is in its locked position and the primary lock is locked, said means being engaged by a movement of the door before the primary lock is locked and disengaged by a movement of the door after the primary lock is unlocked.
55. 19. The combination with a primary lock and a recording lock both adapted to fasten a door in the same position, of means to prevent the advance and retraction of the bolt of the recording lock when the primary lock is locked.
60. 20. The combination with a primary lock and a recording lock both adapted to fasten a door in the same position, of means coactive between the bolt and keeper of the recording lock which render said bolt inoperative when the primary lock is locked.
65. 21. The combination with a primary lock adapted when operated to fasten a door in its locked position, of a recording lock also adapted to fasten the door in its locked position, said recording lock comprising means which render it inoperative when the door is in its locked position, said means being engaged or disengaged by a movement of the door.
70. 22. The combination with a primary locking mechanism adapted when operated to fasten a door in its locked position, of a recording lock also adapted to fasten the door in its locked position, said recording lock comprising means which render it inoperative when the door is in its locked position.
75. 23. The combination with a primary lock adapted when operated to fasten a door in

1
its locked position, of a recording lock also adapted to fasten the door in its locked position, said recording lock comprising means which render it inoperative when the primary lock is locked, said means being engaged and disengaged by a movement of the door.

24. The combination with a primary lock adapted when operated to fasten a door in its locked position, of a recording lock also adapted to fasten the door in its locked position, said recording lock comprising means which prevent the advance or retraction of its bolt when the door is in its locked position and the primary lock is locked, said

means being engaged and disengaged by a movement of the door.

25. The combination of a door, with a primary lock and a recording lock both adapted to simultaneously retain the door locked, 20 said recording lock being provided with means to prevent advance or retraction of its bolt when the primary lock is locked.

In testimony whereof I hereunto affix my signature in the presence of two witnesses. 25

CLARENCE V. DOYLE.
